Patented Dec. 29, 1908.

UNITED STATES PATENT OFFICE.

DAVID ALLEN MURPHY, OF WESTMOUNT, QUEBEC, CANADA.

PRESSURE-APPLYING MACHINE.

No. 907,853.

Specification of Letters Patent.

Patented Dec. 29, 1908.

Application filed February 13, 1908. Serial No. 415,777.

To all whom it may concern:

Be it known that I, DAVID ALLEN MURPHY, of Westmount, Province of Quebec, Canada, have invented certain new and useful Improvements in Pressure-Applying Machines; and I do hereby declare that the following is a full, clear, and exact description of the same.

My invention has for its object to provide a pressure applying machine to maintain a uniform high pressure during a certain definite portion of the action of the operative member thereof, and to this end the invention may be said briefly to consist of the combination with the operative member of such machine, of intermediary means between the initial power exerting member and the operative member whereby a force is transmitted increasing to a maximum attained before the completion of the operative movement and maintaining such maximum throughout the balance of the said movement.

For the purposes of illustration I have shown my invention applied to a riveter in which the operative member is the ram and the initial power exerting member the cylinder and piston.

The well known type of riveter in connection with which I have illustrated my invention utilizes piston driven oscillatory tension links pivoted at their lower ends to the frame of the machine and a compression link oscillated by the same piston and pivotally connected to the ram, the action being that the reciprocation of the piston confined by the tension links within a certain fixed radius causes the compression link to exert a toggle action upon the ram and alternately force it downwards in its power stroke, and return it to its normal position. In this instance the invention is applied to the tension links which are constructed to contract slightly when the piston is finishing its operating stroke for the purpose of causing the ram to operate with a force increasing until it attains a maximum which it does before the completion of its stroke, and maintain this maximum force through the balance of the stroke.

The invention further consists of a simplified piston operating gear.

For full comprehension, however, of my invention reference must be had to the accompanying drawings forming a part of this specification, wherein corresponding refer-

ence numerals indicate the same parts, and in which—

Figure 1 is a side elevation of a riveter provided with my invention, the cylinder being partly broken away; Fig. 2 is a front elevation with one half in transverse vertical sectional view; Figs. 3 and 4 are detail views illustrating the links in different working positions; and Fig. 5 is a diagram illustrating the leverage action of my invention.

The cylinder *b*, piston *c*, piston rod *d*, compression link *e*, ram *f* and frame *g* including the ram guide *k* are of usual construction and therefore will not be described in detail. The usual stops *m* are provided at the opposite sides of the ram guide to limit the forward stroke of the tension links. These tension links are, according to my invention, each formed of a lower member *2* pivoted at its lower end as at *3* to the ram guide, and a pair of upper members *4* located at opposite sides of and pivoted at their lower ends, as at *5*, to the upper end of the lower member, while the upper ends of such members *4* are pivotally mounted upon a pin *6* which also has the end of the piston rod *d*, and the upper end of the toggle or compression link *e* pivoted thereon. The lower members *2* of the tension links are formed with projections *7* adapted to come into contact with the stops *m* which arrest such link members before they come to a vertical position, while the opposite side of each of the upper link members *4* have bosses *8* presenting shoulders adapted, when the lower and upper members are in line, to make contact with an arm *10* of *T* form extending from the said lower member.

When the piston is in its full back position the lower and upper members of each tension link are in alignment. As the piston moves in its power stroke these members maintain such alignment until the lower members come into contact with the stops *m* thereby causing these links to contract as the piston continues to the end of its stroke and turns the upper member on the lower member thus shortening the distance between the pivot points *3* and *6* and forcing with practically uniform leverage, the compression toggle link and the ram downwardly to a proportionally greater extent.

In order to maintain the lower members *2* of the tension links yieldingly in their proper working positions, a pair of small cylinders *15* are fixed to and located one at each side

of the machine frame, and each contains a spring 16 and a piston 17, while such pistons are connected at 18 to the said lower members. These yielding devices have no function to perform unless the machine is operated without rivets being fed thereto.

In order to economize motive fluid in the return stroke of the piston and at the same time enable the machine to be operated by a 10 valve 19 controlling the supply of the fluid to one side only of the piston, a pair of comparatively small bore cylinders 20 project from the cylinder head 21 and communicate with the interior of the main cylinder and 15 pistons 22 within such cylinders 20 are connected to the main piston by piston rods 23. A branch pipe 24 leading from the main motive fluid supply pipe (not shown) is connected to the outer ends of these small bore 20 cylinders and a power is thus maintained just sufficient to return the piston and which will not appreciably interfere with the movement of the piston in its power stroke.

In the present embodiment of my invention 25 the parts of the machine are assembled and adjusted to cause the piston rod in completing its possible stroke to carry the upper end of the toggle or compression link *e* a short distance beyond the axial line of the 30 ram, but if desired such arrangement can be varied to cause the limit of its stroke to be in the axial line of the ram or at any angular position relatively thereto within reasonable limits without changing the force of the ram.

35 Operation: During the power stroke, the members of each tension link move in unison (as if in one piece) with the piston rod and up to the moment the lower members 2 are stalled by the stops *m* the action of the 40 machine is exactly as heretofore in this type of riveter, in that the compression link forces the ram downwardly. In the machines as formerly constructed, however, the contact of the tension links with the stops 45 was the limit of the power stroke of the ram. With this invention, however, the lower members being stopped the upper members 4 turn thereon, the tension links thus contract and shorten the distance between their 50 extremities and consequently as their lower ends are fixed against other movement than rotary the effect is that the ram is driven downwards beyond the position it momentarily assumes when the lower members were 55 stopped, and during the remainder of the stroke while the piston rod continues until the ram is stalled by the work or the piston rod reaches the limit of its possible stroke, the ram is forced downwardly with practically uniform leverage due to the fact that the upper member 4 of each contractible link rotates around the center 5 and that the compression link *e* travels with it without such members appreciably changing their 60 relative angular position (see Fig. 5), with

the result that a practically uniform compressive force is exerted from the time the tension links commence to contract until the ram is stalled. This action is due to the following conditions: The maximum force is 70 attained when the points 3, 5, 6 are in line, or in other words at the instant the link 2 is stalled by the stop *m*. In diagram, Fig. 5, the full lines illustrate the parts in the position they momentarily assume at the instant such maximum force is attained, and the dotted lines indicate the parts in the positions they assume at the end of the stroke. The imaginary line *Y* extending at right angles from the center line of the ram to the center 5 fixed by the stalling of link 2 as just described, remains of constant length throughout the balance of the stroke, while the imaginary line *V* extending at right angles from the line *P* (denoting the line of force of the piston rod) to the said center 5, also remains of practically uniform length. Therefore because the force *P* is constant and the distances represented by the lines *V* and *Y* remain practically constant, the 85 force exerted by the ram during the balance of the stroke is also practically constant, and consequently the maximum force attained when the points 3, 5 and 6 are in line is maintained throughout the balance of the 90 stroke.

What I claim is as follows:

1. The combination with a ram, a power driven member movable across the direction of movement of the ram, a contractible member operatively connecting the power driven member to the ram, and means for causing the said member to contract and during contraction exert its maximum force.

2. In a riveter, the combination with the 105 frame of the machine, a ram, a piston rod and a toggle link operatively connecting the piston rod to the ram, of a jointed link connecting the piston rod to the frame of the machine, and means for causing the said link to bend before the completion of the 110 power stroke of the piston.

3. In a riveter, the combination with the 115 frame of the machine, a ram, a piston rod and a toggle link operatively connecting the piston rod to the ram, of a jointed link connecting the piston rod to the frame of the machine, and a stop upon the frame for causing the said link to bend before the completion of the power stroke of the piston.

4. In a riveter, the combination with the 120 frame of the machine, a ram, a piston rod and a toggle link operatively connecting the piston rod to the ram, of a jointed link connecting the piston rod to the frame of the machine, and constructed to bend in one direction only and means for causing the said link to bend before the completion of the power stroke of the piston.

5. In a riveter, the combination with the 130

frame presenting a ram guide, a ram slidable in the guide, a piston rod reciprocating transversely to the direction of motion of the ram, and a toggle link pivotally connected at one end to the piston rod and its opposite end to the ram, of a pair of contractible links connected at their upper ends to the piston rod coaxially with the pivotal connection of the toggle link, and at their lower ends to opposite sides of the ram guide, and means whereby the said pair of links are caused to contract before the completion of the stroke of the piston.

6. In a riveter, the combination with the frame presenting a ram guide with laterally extending stops at its opposite sides, a ram slidable in the guide, a piston rod reciprocating transversely to the direction of motion of the ram, and a toggle link pivotally connected at one end to the piston rod and its opposite end to the ram, of a pair of links adapted to bend in one direction and connected at their upper ends to the piston rod coaxially with the pivotal connection of the toggle link, and at their lower ends to opposite sides of the ram guide, each link of the said pair consisting of upper and lower members carrying devices preventing bending in the opposite direction, the lower members being adapted to engage the said stops whereby the said pair of links are caused to contract before the completion of the stroke of the piston.

7. In a riveter, the combination with the

frame of the machine, a ram, a piston rod and a toggle link operatively connecting the piston rod to the ram, of a jointed link connecting the piston rod to the frame of the machine, and constructed to bend in one direction only means yieldingly retaining the members of each jointed link in working position, and means for causing the said link to bend before the completion of the power stroke of the piston.

8. In a riveter, the combination with the frame of the machine, a ram, a piston rod and a toggle link operatively connecting the piston rod to the ram, of a jointed link connecting the piston rod to the frame of the machine, and constructed to bend in one direction only, a pair of cylinders each containing a spring and a piston, and a pair of rods projecting from the pistons, the cylinders being secured to the machine frame at opposite sides thereof and the rods to the lower members yieldingly retaining the members of each jointed link in working position, and means for causing the said link to bend before the completion of the power stroke of the piston.

In testimony whereof, I have signed my name to this specification, in the presence of two subscribing witnesses.

DAVID ALLEN MURPHY.
